UNITED STATES PATENT OFFICE

GLENN W. CARPENTER, OF SCHENECTADY, NEW YORK, ASSIGNOR TO GENERAL ELECTRIC COMPANY, A CORPORATION OF NEW YORK

ELECTRIC APPARATUS

Application filed October 30, 1925. Serial No. 65,862.

My invention relates to electric apparatus comprising a plurality of thermionic electron discharge devices, and has for its principal object the provision of circuit arrangements for connecting the cathodes of the devices to a source of heating current either in parallel or series with one another and for excluding the anode current of each device from the cathode circuits of the remaining devices 10 when the cathodes are connected in series.

It is frequently desirable that the cathodes of thermionic discharge devices comprised in an electric apparatus, such as a radio receiving outfit, be adopted to be supplied with 15 heating current either from a low voltage battery or from a high voltage source of rectified current. The cathodes may be connected in parallel to the low voltage source and in series to the high voltage source. If the cathodes are connected in series to the high voltage source, difficulty is encountered due to 20 the fact that the anode currents of some of the devices. In accordance with my invention this difficulty is avoided by connecting each 25 cathode in parallel with a shunt having a resistance value dependent on the magnitude of the anode current that tends to be transmitted through the cathode.

My invention will be better understood 30 from the following description when considered in connection with the accompanying drawing and its scope will be pointed out in the appended claims.

Referring to the drawing, Fig. 1 shows a 35 receiving apparatus provided with a graded resistance element which is located outside the apparatus casing and is adapted to complete a series connection between the cathodes of the devices comprised within the casing; 40 Fig. 2 shows an integral bus structure adapted to replace the resistance element for connecting the cathodes in parallel with one another; Fig. 3 is a diagrammatic representation of the circuits of the apparatus; and Fig. 45 illustrates certain details of the circuit connections.

Fig. 1 shows a receiving apparatus comprising a casing 1 provided with terminals 2 to 20 which are adapted to be connected either

to taps 22 to 30 of a resistance element 31, or to taps 32 to 50 of an integral bus structure 51. Suitable means, such as screws threaded into the terminals 2 to 20, are provided for maintaining contact between the different sets of taps and the terminals. The upper ends of the taps of the resistance element and bus structure are slotted so as to be readily slid under the heads of the screws and clamped into contact with the terminals 55 mounted on the casing. The connections made by resistance element 31 and bus structure 51 respectively will be readily understood from Fig. 3.

Fig. 3 diagrammatically shows a plurality 60 of thermionic electron discharge devices 52 to 59 which are mounted above the casing 1 in sockets in the top of the casing and are provided respectively with cathodes 60 to 67, grids 68 to 75, and anodes 76 to 83. It will 65 be observed that the terminals 2 and 4 to 19 are connected to the grid and cathode leads of the devices 52 to 59, that leads 84 and 85 are connected respectively to terminals 20 and 3 are provided for transmitting heating current to the cathodes 60 to 67, and that the anode currents of the devices 52 to 59 may be 70 transmitted through lead 85 and suitable leads 91, 92 and 93 connected to the anodes of the various devices, through the circuit arrangement 75 illustrated by Fig. 4.

This arrangement comprises conductors 94 and 95 adapted to be connected to a suitable source for transmitting rectified alternating current to the valves 52 to 59 through smoothing means, shown as reactors 96 and condensers 97, and through a resistor 98 which is grounded at one end through a condenser 99 and is partly shunted by a glow tube 100 for maintaining a constant voltage drop across 80 the shunted portion of the resistor. The resistor 98 is provided with terminals 84', 85', 91', 92', and 93' which are connected respectively to the terminals indicated in Fig. 3 by the corresponding unprimed reference numbers.

Assuming the bus structure 51 to be connected to the terminals 2 to 20, the cathodes 60 to 67 are connected to the bus conductors 86 and 87 in parallel, the bus conductors 86 and 100

87 are connected to the leads 84 and 85 respectively, the grids 68 to 72 and 74 are connected to grid bus conductor 88 and the cathode 61 is connected to the cathode 62 through 5 a bus conductor 89 and an adjustable resistor 90 that is provided for purposes of volume control. With these connections, current is supplied to the parallel connected cathodes through leads 84 and 85 and the voltages of 10 grids 68 to 72 and 74 are dependent on the potential of grid bus 88. The grid 73 is connected to the cathode 65 for the reason that device 57 is utilized as a detector. The potential of grid 75 may be derived from a separate 15 source. Under the conditions described, there is no tendency for the anode current of one device to be transmitted through the other devices because the cathodes are connected in parallel with one another.

20 With the resistance element connected to the terminals 2 to 20, the cathodes of the various devices are connected to leads 84 and 85 in series with one another and are shunted by different sections of the resistance element 25 31. If the resistance element were omitted, the anode current of each device would be transmitted through all the succeeding devices. Thus with the source of current supply connected as shown, the sum of all the 30 anode currents would be transmitted through cathode 67. This difficulty is avoided by connecting different sections of the resistance element 31 in shunt with the cathodes of the various devices, the resistances of the various 35 sections being graded to maintain the potential drops of all the filaments at the same value. With these sections properly determined by the contact points of terminals 22 to 30 of the resistance element 31, the apparatus 40 may be readily adapted to utilize a low voltage battery or a high voltage source of rectified current for heating the cathodes of the various devices. It should be noted that the resistance element 31 serves both to maintain 45 the cathode current at a constant value throughout the heating circuit and to determine the bias of grids 68 to 72 and 74 which are connected to the corresponding cathodes through different sections of the resistance 50 element. In case the cathode of one tube should burn out the cathodes of the other tubes would remain lighted by current flowing through the shunt and the defective tube 55 can be readily located.

The embodiment of the invention illustrated and described herein has been selected for the purpose of clearly setting forth the principles involved. It will be apparent, however, that the invention is susceptible of being modified to meet the different conditions encountered in its use and I therefore aim to cover by the appended claims all modifications within the true spirit and scope of my 60 invention.

What I claim as new and desire to secure by Letters Patent of the United States, is:

1. The combination of a plurality of electron discharge devices each provided with a cathode and an anode and with a grid arranged to control the current transmitted between said cathode and anode, a receptacle provided with sockets for said devices and with a plurality of terminals mounted on the outside of said receptacle, circuit connections enclosed within said receptacle and connected between said terminals and said sockets, and an impedance device provided with taps arranged to engage said terminals for connecting the cathodes of said electron discharge devices in series and causing a bias potential to be applied to said grids. 70

2. The combination of a plurality of electron discharge devices each provided with a cathode and an anode and with a grid arranged to control the current transmitted between said cathode and anode, a receptacle provided with sockets for said devices and with a plurality of terminals mounted on the outside of said receptacle, circuit connections enclosed within said receptacle and connected between said terminals and said sockets, and a resistor provided with taps arranged to engage said terminals and connect the cathodes of said devices in series with 90 one another. 85

3. The combination of a plurality of electron discharge devices each provided with a cathode and an anode and with a grid arranged to control the current transmitted between said cathode and anode, a receptacle provided with sockets for said devices and with a plurality of terminals mounted on the outside of said receptacle, circuit connections enclosed within said receptacle and connected between said terminals and said sockets, and an impedance device provided with taps arranged to cooperate with said terminals for connecting the cathodes of said devices in series with one another and to complete circuits whereby the heating currents of said anodes are maintained equal irrespective of the anode currents of said electron discharge devices. 100

4. The combination of a plurality of electron discharge devices each provided with a cathode and an anode and with a grid arranged to control the current transmitted between said cathode and anode, a receptacle provided with sockets for said devices and with a plurality of terminals mounted on the outside of said receptacle, circuit connections enclosed within said receptacle and connected between said terminals and said sockets, an impedance device provided with taps arranged to cooperate with said terminals for connecting the cathodes of said devices in series with one another, and a bus structure provided with taps arranged to cooperate 110 with said terminals to connect the cathodes 120 125 130

of said electron discharge devices in parallel with one another.

5. The combination of a plurality of electron discharge devices each provided with a cathode and an anode and with a grid arranged to control the current transmitted between said cathode and anode, a receptacle provided with sockets for said devices and with a plurality of terminals mounted on the 10 outside of said receptacle, circuit connections enclosed within said receptacle and connected between said terminals and said sockets, and a bus element provided with taps arranged to cooperate with said terminals to connect 15 the cathodes of said electron discharge devices in parallel with one another.

In witness whereof, I have hereunto set my hand this 29th day of October, 1925.

GLENN W. CARPENTER.

20

CERTIFICATE OF CORRECTION.

Patent No. 1,864,482.

June 21, 1932.

GLENN W. CARPENTER.

It is hereby certified that error appears in the printed specification of the above numbered patent requiring correction as follows: Page 1, line 14, for "adopted" read adapted, and line 23, after "devices" insert the words are transmitted through the cathode circuits of other devices; and that the said Letters Patent should be read with these corrections therein that the same may conform to the record of the case in the Patent Office.

Signed and sealed this 27th day of September, A. D. 1932.

M. J. Moore,
Acting Commissioner of Patents.
